SUPPORTING AND LOCKING MEANS FOR
PRINTING INTERPRETERSHarold P. Mixer, Floral Park, N. Y., assignor to
Remington Rand Inc., Buffalo, N. Y., a corpora-
tion of Delaware

Application August 3, 1934, Serial No. 738,171

5 Claims. (Cl. 101—93)

This invention relates to an improvement in supporting and locking devices, and is particularly adapted to the Powers printing interpreters disclosed in the patent application of William W.

5 Lasker, Serial Number 637,401, filed October 12, 1932.

In the machine disclosed in the above cited Lasker application, it is necessary that the interpreter plates be put into or taken out of said 10 machine one by one, to correct troubles such as a jammed card, the replacement of a printing ribbon, etc. By incorporating the improvements disclosed in the present application with the machine disclosed in the above cited Lasker 15 application, the need for the above described tedious removal or change of plates is obviated. Groups of plates may be assembled into single units for use in certain differing fields, such as alphabetic or numeric. A hinged frame is 20 provided in this invention, which is adapted to carry the printing interpreter plates. With the incorporation of this frame, it becomes quite a simple matter to remove jammed cards or replace a ribbon, merely requiring the lifting of 25 said frame on its hinge member.

Another feature of this invention is the provision of means whereby said frame can be lifted at but one small part of a cycle of operation of said printing interpreting machine, at 30 which part of said cycle all the sensing pins are in their lower position, and no great damage would be done to the mechanism, should said frame containing said plates, be dropped accidentally.

35 Still another feature of this invention is that should said frame be raised and the drive mechanism moved, said frame will be automatically blocked against downward movement, and held at a point where the lowest extremities of the 40 stops mounted on the printing interpreting plates which are in turn mounted in said rockable frame, will be clear of any interponents of the sensing mechanism which may be elevated.

One object of this invention is to provide a 45 movable frame adapted to carry a plurality of interpreter plates.

Another object of this invention is to provide an automatic locking mechanism operable upon a movable frame in such a way as to prevent 50 damage being done to the mechanism of a printing interpreting machine by accidentally dropping said frame.

Another object of this invention is to provide a 55 device wherein groups of interpreter plates can be fastened together as a single unit.

Other objects and structural details of the invention will be apparent from the following description when read in connection with the accompanying drawings, wherein:

Fig. 1 is an isometric view of a printing interpreting machine showing the plate carrying frame in a partially raised position and one of its holding set screws in an exploded position.

Fig. 2 is an isometric view of a group of interpreter printing plates assembled as a single 10 unit.

Fig. 3 is a fragmentary isometric view showing the means used to hold the lower front ends of a group of interpreter printing plates.

Fig. 4 is a front view of Fig. 2.

Fig. 5 is a sectional view showing the movable frame and locking mechanism.

Fig. 6 is a fragmentary sectional view showing the relations between the latching pins and the interpreter plate stops.

Referring particularly to the drawings, the method of assembling a group of interpreter plates is shown in Figs. 2, 3, and 4. References to the forward end of the mechanism in Figs. 2, 3, 5, and 6 are directed to the left side in 20

all of said views. Because of the multiplicity and thicknesses of parts mounted to each plate, and the close relationship of plates to each other, when placed in a printing interpreter, it becomes quite a problem to assemble a group of plates as 30

a single unit, particularly in the lower front region. To hold the lower front part of a group of interpreter plates 1 in such a relation to each other as to be adapted to fit into the plate 35

grooves of a printing interpreter machine, said plates 1 are set in crenellations 2 in an angle member 3 in such a way as to have said angle member 3 fit against the lower front corner of the stop retaining member 4 (Fig. 2). The crenellations in angle member 3 are wide enough to 40

allow a slight amount of sidewise movement of plates 1. A multiplicity of hooked angle members 5 are then set between plate 1 and member 4 and around the rivet 6 after which the downwardly extending leg of member 5 is bent over 45

to lock said hooked angle member 5 in position (Fig. 4). The length of angle member 3 is governed by the number of interpreter plates, which may be desired to be assembled as a unit. The other three holding and spacing devices 7, 50

used for assembling a group of interpreter plates 1, are heavy crenelated bars, which space and hold said group of plates in alignment. The two upper spacing and holding devices 7 have hinged handles pivoted thereto to facilitate handling. 55

To facilitate the clearing of a printing interpreter of a jammed card, the replacement of ink-ribbons, etc., this invention includes the incorporation of a rockable frame 8 (Fig. 5), pivotally supported by the main framework and adapted to hold a group of interpreter plates 1, with the printing interpreting machine disclosed in the above cited Lasker applications.

During a cycle of a printing interpreter there are times when one or more stops 9 (Fig. 6), may be elevated by the sensing mechanism and held elevated by the action of their corresponding locking slides 10 upon corresponding interponents 11. Now, it may be seen that with the incorporation of frame 8 in a printing interpreter, it would be possible to rock said frame 8 when the mechanism is in the above cited position. To lift or rock frame 8 it is necessary that universal retract bar 12 (shown diagrammatically in Fig. 6), be removed thereby allowing all the measuring bars 13 to be drawn forwardly by their springs. Should frame 8 be accidentally dropped when the mechanism is in the above stated condition, (interponents 11 elevated and measuring bars 13 forward), serious damage would be done to either the interpreting printing plates or the sensing mechanism or both. To safeguard against such damage being done, a locking mechanism has been provided (Figs. 1 and 5). This locking mechanism includes a stud 14 fixed to frame 8 in such a manner as to be adapted to engage a slot 15 in a reciprocatory locking plate 16 mounted to a side frame 17 of the printing interpreter. In the printing interpreting machine disclosed in the above Lasker application, a cam-operated spring-held universal bail 18 is provided for actuating all of the bell cranks 19 (Figs. 2 and 6), to positively restore any stops 9 which may not have returned to normal position after the universal locking slide bail 20 has been actuated. In this invention, universal bail 18 is also adapted to be operable upon locking plate 16. The bail 18 is actuated once during each cycle of said printing interpreting machine, shortly after the latch plates 10 have been actuated by the bail 20, to release any interponents 11 which may have been latched up. As may be seen in Fig. 5 the only time at which locking plate 16 is free to be manually operated is when bail 18 is actuated rearwardly. With locking plate 13 in its rearmost position, it will be seen that stud 14, fixed to frame 8 is clear of obstructions and consequently said frame 8 is free to be rocked. When the roller cams 21 (one not shown), are not actuating the levers 22 (one not shown), which carry said universal 18, the springs 23 (one not shown), cause the levers 22 to resiliently hold said bail 18 in its forward position. When frame 8 is in position for normal operation of the cited Lasker machine, and locking plate 16 is pushed forwardly by bail 18, slot 15 will engage stud 14 fixed on frame 8, to lock said frame 8 against being moved. If locking plate 16 should be actuated to locking position by movement of shaft 24 while frame 8 is raised and an attempt then made to lower said frame 8 to operating position, the stud 14 on said frame 8 will engage the surface 25 of locking plate 16 and thereby block further downward movement of said frame 8 until said shaft 24 is turned to a point where cams 21 enable the manual rearward movement of said locking plate 16.

As shown in the above cited Lasker application, the levers 22 are single arm levers operating only on bell-cranks 19. If this single-arm type of lever is used with the present frame 8 it is pos-

sible to press the locking plate 16 rearwardly against the tension of the spring 23 to lift frame 8. To eliminate this possibility an arm 26 carrying a roller 27 has been added to one of the spring-held levers 22 (Fig. 5). Also, to the shaft 24, a notched disc 28 has been added in such a position as to have its periphery engageable by said roller 27. During normal operations of the printing interpreting machine the roller 27 does not contact the periphery of said notched disc 28; however, if an attempt be made to manually render the locking plate 16 ineffective at any but the proper time the roller 27, after a very short travel, will contact the periphery of notched disc 28 and thereby prevent the manual operation of locking plate 16. A pair of locking screws 29 (Fig. 1, one not shown) are provided to hold frame 8 solidly during operation of the printing interpreter machine.

While there are above described but two embodiments of the invention, it is possible to produce still other embodiments without departure from the inventive concept above disclosed, and it is, therefore, desired that only such limitations shall be imposed on the appended claims as are states therein, or required by the prior art.

What I claim as new, and desire to secure by Letters Patent, is:

1. In a printing interpreting machine of the class described, in combination, means for assembling a group of printing interpreting plates as a single unit, a rockable frame adapted to hold a plurality of such single units, means for automatically locking said rockable frame against movement, automatic means for preventing the return of said rockable frame to its normal operative position, and means whereby said locking means can be rendered ineffective.

2. In a printing interpreting machine of the class described in combination, a supporting framework, an intermediary rockable frame pivoted in said supporting frame and adapted to hold one or more perforation interpreter plates, and reciprocatory locking means adapted to lock said intermediary rockable frame in and out of normal position.

3. In a locking and holding means of the class described, in combination, a supporting framework, rockable means mounted to said supporting framework and adapted to hold one or more perforation interpreter plates, reciprocatory locking means pivoted to said supporting framework and operable upon said rockable means, and means for automatically actuating said locking means.

4. In a printing interpreting machine of the class described, in combination, means for assembling a group of interpreting printing plates as a single unit, movable means adapted to hold one or more interpreting printing plates, means for automatically locking said movable holding means, and means for automatically preventing the return of said movable holding means to normal operating position.

5. In a printing interpreting machine of the class described, in combination, a supporting framework, an intermediary crenelated rockable frame pivoted in said supporting framework and adapted to hold one or more perforation interpreter plates, a stud fixed on said intermediary frame, a reciprocatory locking slide mounted on said supporting framework and having a lug which is adapted to co-act with said stud to either lock said intermediary frame in operating position, or, to block said intermediary frame from attaining operating position, a pair of spring held

levers pivoted on opposite sides of said supporting framework, a connecting bail mounted between the upper ends of said levers and adapted to resiliently push said locking slide to its locking position, a main drive shaft, a pair of roller cams connected to said shaft and which roller cams actuate said levers once during each revolution of said shaft to rock said bail and thereby enable

the manual unlocking of said reciprocating locking plate, an arm extension on one of said levers, a roller pivoted to the extremity of said arm extension, and a notched disc fixed to said shaft in such a manner as to positively prevent the actuation of said levers. 5

HAROLD P. MIXER.
